G. E. OAKLEY

TRAIN DOOR SYSTEM

Filed Feb. 28, 1920

UNITED STATES PATENT OFFICE.

GEORGE E. OAKLEY, OF ALBANY, NEW YORK, ASSIGNOR TO CONSOLIDATED CAR-HEATING COMPANY, OF ALBANY, NEW YORK, A CORPORATION OF WEST VIRGINIA.

TRAIN-DOOR SYSTEM.

Application filed February 28, 1920. Serial No. 362,168.

To all whom it may concern:

Be it known that I, GEORGE E. OAKLEY, a citizen of the United States, residing at Albany, in the county of Albany and State of New York, have invented certain new and useful Improvements in Train-Door Systems, the following being a full, clear, and exact disclosure of the one form of my invention which I at present deem preferable.

For a detailed description of the present form of my invention, reference may be had to the following specification and to the accompanying drawings forming a part thereof, wherein—

Fig. 1 is a diagrammatic view of my system circuits,

Fig. 2 is a detail.

My invention relates to the electrical operation of all or part of the doors in a train simultaneously from a single point. It has been old for many years to interconnect the door-opening and the door-closing circuits throughout two or more cars of a train by means of train wires, so that by the closing of a single switch, current may be delivered to all of said circuits at once and all of the doors simultaneously opened or simultaneously closed. My invention relates to several features of improvement in such a system, the principal one being an arrangement by which a guard stationed at any intermediate point of the train along the station platform may close, in one separate group, those doors between his station and the head end of the train, and in another separate group, those doors between his station and the rear end of the train. Other features of my improvement will be described and claimed hereinafter.

The accompanying drawing shows in diagram, the circuits for one car and the end of an adjoining car of a train, it being understood that these circuits are duplicated in each of the entire series of cars. Wires 5, 6, 7, and 8, are the train-wires extending through the train and connected from car to car by jumpers J. Train-wires 5 and 8 are for the door-opening operation, the doors on one side of the train being operated by wire 5 and those on the opposite side by wire 8. Train-wires 6 and 7 are for the closing of the doors on the respective sides of the train, it being remembered that ordinarily it is desired to open and close at one time only those doors which are

on the side of the train adjacent to the platform of the station at which the train may be stopping. From the door-opening train-wires 5 and 8, branch wires 15¹ and 15 extend to the relay magnets 16¹ and 16 at 60 L¹ and L respectively and thence to ground. All of the relay magnets 16 on the several cars will therefore be energized whenever the train wire 8 is connected, as by means of a push-button switch, to one terminal of a battery whose opposite terminal is grounded and similarly all the relay magnets 16¹ will be energized by the train-wire 5 when it is connected to the battery aforesaid. Each relay 16, when energized, 70 brings a contact plate 17 into engagement with three contacts, each of which forms one terminal of a wire 18, and also into engagement with a fourth contact that forms the terminal of battery bus-wire B⁺, which 75 is the wire leading from the positive terminal of the battery (not shown) to those points of the circuit where current is required for operation of the doors. Each of the three wires 18 goes by a wire 19 to a door-opening magnet 20 and thence to ground. It is not necessary here to show or describe the well-known door-engine and valves by which the magnet 20 causes the 80 opening of the door since they form no part 85 of my present construction and may be of any suitable kind. The door-opening arrangements for the opposite side of the car are identical with those just mentioned. For closing the doors relays 22 and 22¹ are 90 provided at K and K¹ for the respective sides of the car, in branches from train-wires 6 and 7. The door-closing magnets are 26 and 26¹ similar to door-opening magnets 20 and 20¹ and supplied by wires 24 and 24¹ controlled, similarly to aforesaid wires 18 and 18¹, by the relay-magnets 22 and 22¹. In the circuit of each magnet 26 or 26¹ is a switch 25 or 25¹ opened by a magnet 27 or 27¹ as will be described later. 95

In Fig. 2, I have indicated by A the ordinary door-closing arm of a pneumatic door-engine, which, as is customary, stands in a substantially horizontal position when the door is closed. It is usual to have this door arm operate a switch N to close a signal circuit 4, 5, when it closes the door and when all the doors are closed this signal circuit is completed and the motorman at the head of the train thereby notified to proceed. In 105 110

addition, I provide two back-stop contacts for the said switch N connected respectively to the battery bus-wire B and to an electric lamp M. These contacts are closed so long as the arm is out of its door-closing position and the lamp M lighted. This lamp may be a red lamp and will indicate, so long as it is lighted that the door is not closed. In the diagram of Fig. 1, I have shown in diagram 10 the said switch N and lamp M controlled thereby. I have also shown at each door two bars 28 and 29 with which two contact springs 30 and 31 make contact while the door is moving back and forth but break 15 contact therewith when the door is fully closed, as is now well known in the art and described in McElroy Patent No. 1,287,717 of Dec. 17, 1918. These two bars become connected electrically by the action of a 20 movable shoe or fender on the front edge of the door in the event of the door meeting an obstruction and thereby a circuit is closed from the battery bus-wire B⁺ to relay magnet 27 and door-opening magnet 20. 25 Thus in the event of the door encountering an obstruction it is automatically opened, and the relay magnet 27 acts at the same time to open the switch 25, heretofore mentioned, and thereby break the circuit leading 30 to door-closing magnet 26, so that the aforesaid automatic opening of the door can not be interfered with by the manual door-closing push-buttons. I have also shown at each door two push-buttons 33 and 34. The pressing 35 of button 33 connects the battery bus-wire B⁺ to door-closing magnet 26 and the pressing button 34 connects it to door-opening magnet 20. Thereby the individual door corresponding to the buttons 33 and 34 may 40 be opened or closed, it being remembered that the train line relay magnets 22 and 16 at K and L normally hold open the wires leading to the door-opening and door-closing magnets, so that the current admitted 45 to those magnets by buttons 33 and 34 does not go beyond them to work other doors in the train or even in the same car. These buttons 33 and 34 I purpose to locate on the outside of the car, where, being locked in the 50 customary way against unauthorized operation, they may be used by the trainmen to enter the car when it is in the train yard, or under other conditions when he desires to operate only a single door instead of all the doors in the train.

I next call attention to the arrangement at the points H which I designate as guard-stations. Here the adjacent train-wires, e. g. closing wire 7 and opening wire 8, are interrupted and the severed ends brought into the station and connected to contacts which are normally bridged by contact blocks 13 and 14. When so bridged the electrical continuity of the wires is maintained. The retraction of contact block 14 opens train-

wire 8. The retraction of block 13 opens train-wire 7 and in addition connects the wire S to the battery bus-wire B by means of back-stop contacts. When the wire S is so connected, it enables push-button 9 to connect the battery to that part of train-wire 8 which extends to the right of guard-station H—say towards the head-end of the train,—and push-button 12 to similarly connect the battery to that part of train-wire 8 which extends to the left of guard-station H—towards the rear end of the train. At that time, too, button 10 can connect the battery to the righthand section and button 11 to the left hand section of the door-closing train-wire 7. This guard station will be located on the outside of the car, one at each of the diagonally opposite corners of the car, as shown in the drawing, so that a guard standing on the station platform can have ready access to it, by means of a key. The unlocking action draws back the two contact blocks 13 and 14, leaving the buttons 9 and 10 in control of the doors on the forward end of the train and buttons 11 and 12 in control of those on the rear end. Therefore, the guard need look toward only the end of the train at a time and by pressing the proper button can open or close the corresponding doors while they are within his view. Since there is such a guard station adjacent to one end of each car, the division between the different sections of train-wires can be located at any one of those stations which may be most convenient to the guard. On the arrival of a train, the guard can step to the nearest guard station and after unlocking it, can open first one group and then the other group of doors along the train; when the train is ready to start, he will, in like manner, close the doors. If he sees the red light M burning at any door, he will thereby know at once which door it is that has failed to close. If no red light remains, it means that all doors are closed, that the motorman has thereby received his signal to go ahead. If desired, a guard on the train may perform this duty.

It will be observed that, while the train is moving, each train-line is continuous, but when the train stops, it is divided into sections by the doorman opening one of the bridging switches 13 or 14. Since said bridging switches are present on each car, as a part of the doorman's apparatus, the sectioning points of a train-line can be selected by the doorman when the train comes to a stop. He will operate those switches 13, 14, which happen to be nearest to his position on the platform, or those which are most convenient, or which may be assigned to him. The sections may include different numbers of cars at the different stops. The sectioning is not fixed or permanent for the train is but a temporary condition at stop- 130

pages, and of a character appropriate to the individual stops. Moreover, in making up a train the train-line is left continuous; there is no sectional train-line until the door-
5 man opens one of the circuit breakers 13, 14, as an incident of his selection of the particular stations at which he will stand when operating the doors, and an incident also of his control apparatus and of his working the 10 doors ahead of him at different times from those behind him in the train.

What I claim as new and desire to secure by Letters Patent is:

1. The combination with door-operating 15 circuits on two or more cars of a train, of a continuous train-line simultaneously controlling said circuits and divisible into sections, an operator's control-apparatus at each operating point on the train, each apparatus

comprising a normally closed circuit-breaker 20 in the said train-line and means for opening said circuit breaker and operating separately the doors ahead of and behind the operator's selected station.

2. The combination with door-operating 25 circuits on two or more cars of a train, of a continuous train-line simultaneously controlling said circuits and divisible into sections, normally closed circuit breakers bridging between said sections during train movement, and means for opening said bridging 30 switches when the train stops and for separately connecting the two adjoining sections to a source of electric current.

Signed at New York, county of New York, 35 State of New York, this 26th day of February, 1920.

GEORGE E. OAKLEY.
